UNITED STATES PATENT OFFICE.

BENJ. KRAFT, OF READING, PENNSYLVANIA.

BOX AND AXLE FOR SAVING OIL.

Specification of Letters Patent No. 8,187, dated July 1, 1851.

To all whom it may concern:

Be it known that I, BENJAMIN KRAFT, of the city of Reading, in the county of Berks and State of Pennsylvania, have invented a new and Improved Box and Journal for Saving Oil; and I do hereby declare that the following is a full and exact description thereof, reference being had to the accompanying drawings and to the letters of reference marked thereon.

Figure 1, a longitudinal section of the box, the division between the upper and lower boxes represented by the dotted line *a, a*. K, represents the journal box. *b, b*, the space between the journal box and the sides of the reservoir.

Fig. 2, a bird's eye view of the lower box. *k* the journal box. *b, b, b, b*, the reservoir on its four sides. S, S, the two ends of the reservoir with their beveled edges.

Fig. 3. The upper box or cap *a, c, b*, forming the V channelled passage for the oil.

Fig. 4. The shaft and journal. H, the portion of the journal bearing on its box. D, D, the two circular channels required in a continuous shaft, one only necessary in an end journal.

Fig. 5. The relative height of the sides of reservoir box and that of the journal box, shown by concentric circles E, F, where E, is the circumference of the journal and F, that of the oil box.

To enable others skilled in the art to make and use my invention I will proceed to describe its construction and operation.

The nature of my invention consists of a box surrounding the journal box, on its sides and ends forming a reservoir for the oil, after its escape from the journal. The sides of this box are on a higher level than those of the box on which the journal revolves, and sufficiently so to enter the circular channel in the shaft, by means of which the lateral flow of oil on the shaft is prevented. The journal box placed in the center of the reservoir with the bottom of the journal box on a higher level than the bottom of the reservoir or oil box and sufficiently above its bottom, allows a groove to be formed around the journal box deep enough to permit the oil, with the impurities, arising from friction of the metal and dust to lie undisturbed

by the revolutions of the journal: by this flow of the oil not only from its ends but also from the under side of the journal it carries with it all impurity, thus preserving the journal and box from destructive wear, and its smoothness unimpaired. Should there be more oil poured on the journal and box, than necessary, it flows into the oil box. The upper box is made smaller than the lower box, and has a V shaped channel to keep the oil in the center of the journal box, preventing its flowing on the shaft.

The journal is without a swell, either inside or outside of the box, having instead thereof a channel or circular groove, sufficiently wide and deep to receive the beveled edge of the oil box, touching it only on the outside shoulder, the journal at this groove does not rest upon the reservoir box, all of its perpendicular bearings being on the single box in the center. The channel cut in the shaft is as wide as the space for the oil and the thickness of the sides of the oil box, and from the side of the channel being in contact with the outside of the oil box, any oil that has crossed the channel, will be removed by the beveled edge of the reservoir. Those raised sides also prevent lateral motion of the shaft from their bearing against the outer shoulders of the channel.

To prevent my invention being misunderstood I would state, it is not for supplying the journal with the same oil, as is the case of Shugert, Davallan and others but in saving it to be used again, after the impurities have subsided: I offer no mechanical device for raising the oil from the reservoir as they do.

I claim—

Causing the beveled edges of the oil box to enter the grooves of the axle and rest against their outer shoulders but not against their inner shoulders—thus at the same time preventing end play and the escape of the oil, the journal bearing being lower than the beveled edges of the oil box and sufficiently above the bottom of it to prevent the oil coming from the box to the journal.

BENJAMIN KRAFT.
